UNITED STATES PATENT OFFICE.

JOSEPH LOCH, OF BROOKLYN, NEW YORK.

ELECTRIC DOOR-OPENER.

No. 852,279.

Specification of Letters Patent.

Patented April 30, 1907.

Application filed April 17, 1906. Serial No. 312,198.

To all whom it may concern:

Be it known that I, JOSEPH LOCH, a citizen of the United States, residing at Brooklyn, in the county of Kings and State of New York, have invented new and useful Improvements in Electric Door-Openers, of which the following is a specification.

This invention resides in certain features of construction by which a simple structure is obtained and one which when released will not prematurely re-engage.

This invention is set forth in the following specification and claim and illustrated in the annexed drawing, in which:

Figure 1 is a side elevation of a door opener embodying this invention. Fig. 2 is a view like Fig. 1 with parts in a different position. Fig. 3 is a section along *w w* Fig. 1. Fig. 4 is a section along *x x* Fig. 1. Fig. 5 is a section along *y y* Fig. 1. Fig. 6 is a section along *z z* Fig. 1. Fig. 7 shows a detent or dictator. Fig. 8 shows the armature.

A casing *a* adapted to be set in a door frame is shown with a catch or bolt *b* swinging on pivot *c*. A spring *d* returns the latch or bolt *b* to engaging or locked position. The catch has an arm or tail to which at *e* is pivoted a slide or connecting piece *f*. This slide pivoted to the bolt connects the bolt and a lever *g*. Said slide straddles the lever or its fulcrum part *h* and can slide on but rotates with the lever. The slit in the connection *f* has parallel or straight edges Fig. 5, and said connection straddles or slides on a similarly shaped part on the lever fulcrum. A sliding non rotary connection is thus made between the parts *f* and *h*.

The free end of the lever *g* can be locked or engaged by an armature *i* and when so locked the bolt *b* is held against motion by the connection *f* straddling the fulcrum *h* of the locked lever *g*. When the armature is attracted or in other words when the magnet *k* has been energized, the lever *g* has been released and by a push or force suitably applied to and rocking the bolt *b* and its tail the slide *f* is caused to slip along or across the fulcrum *h* but without losing engagement therewith.

The armature comprises four lugs, namely the two hinge lugs *i'* for hinge pin *m*, the stop lug *i''* and the locking lug *i'''*. The locking lug engages the lever *g* when locking the same.

When the armature is attracted by the magnet Fig. 2 the lug or lock part *i'''* is

moved to releasing position and the lever *g* is now free to turn or swing for the bolt *b* to be moved or swing to opening position.

To the armature at *o* is pivoted a detent or what might be called a dictator comprising a stop or detent face *p* and a tail or releasing piece *q* and a second tail or armature piece *r*. The detent is shown in Fig. 7. When the armature *i* is attracted by the magnet *k* the tail *r* is likewise attracted and as the armature *i* moves to the magnet the face *p* of the detent comes to rest on a rib or shoulder piece *s* (Fig. 2) of the casing. If now the electric current is interrupted or the magnet *k* deenergized the armature *i* or its lock part *i'''* is nevertheless held back or clear to leave the lever *g* and bolt *b* free to move or the door to be opened. The detent *p* is noticed in Fig. 2 holding the armature *i* clear. 75

As the lever *g* swings back with the opening bolt such lever impinges or presses on the swell or curvature at the free end portion of tail *q* and the detent is thus rocked about pivot *o* a sufficient extent to slip face *p* off the ridge or lug *s* from the position shown in Fig. 2 to that of Fig. 1. The armature *i* is now free and its spring or blade *t* moves such armature back for its locking lap *i'''* to be in position to again engage lever *g*. 85

The lock lap *i'''* is beveled in one direction to allow the lever *g* to return to closing or locking position but said lever *g* cannot open until armature *i* has moved to releasing position. 90

I claim:

1. In an electric door opener, a magnet, an armature, a lever engaged by the armature, and a strike and a slide pivoted to the strike and made to straddle the fulcrum of the lever for connecting the strike and lever. 95

2. In an electric door opener, a magnet and armature, a lever engaged by the armature, a strike, and a slide pivoted to the strike and made to straddle the fulcrum of the lever. 100

3. In an electric door opener, a magnet and armature, a lever engaged by the armature, a strike and a connecting piece pivoted to the strike and made to slide on and non-rotatively engage the lever. 105

4. In an electric door opener, a magnet, a strike controlling the armature, and a dictator or holding device for the armature to hold such armature in releasing position with respect to the strike. 110

5. An electric door opener, comprising a

- magnet, a strike controlling armature, a holding device to keep the armature retracted with respect to the said strike, and a rib or stop for the holding device.
- 5 6. In an electric door opener a magnet, a strike controlling armature, a holding device actuated by the magnet adapted to hold the armature in engagement with the poles of the magnet, and a rib or step for supporting the holding device when holding the magnet in disengaging position.
7. A door opener comprising a magnet, an armature and holding device both within the field of the magnet, said holding device 15 adapted to hold the armature in engagement with the poles of the magnet and a strike engaged by the armature.
8. A door opener comprising a magnet, an armature, a holding device pivoted to the armature and attracted by the magnet, said holding device being adapted to hold the armature in engagement with the poles of the magnet and a strike engaged by the armature.
- 20 25 9. A door opener comprising a magnet and armature with a holding device having an ar-

mature tail or portion attracted by said magnet said holding device being adapted to hold the armature in engagement with the poles of the magnet.

10. A door opener comprising a strike and lever, an armature for engaging the lever, and a holding device for the armature having a releasing tail or arm, said holding device being adapted to hold the armature in engagement with the poles of the magnet.

11. A door opener comprising a strike and lever, an armature for engaging the lever, and a holding device for holding the armature in engagement with the poles of the magnet said holding device having a releasing tail or arm, said releasing tail being placed in the path of the lever, to move the holding device to releasing position by said lever.

In testimony whereof I have hereunto set 45 my hand in the presence of two subscribing witnesses.

JOSEPH LOCH.
